US00D871089S

(12) United States Design Patent (10) Patent No.: US D871,089 S
(45) Date of Patent:  *Dec. 31, 2019

(54) BENCH

(71) Applicant: ARPER S.P.A., Monastier di Treviso
(IT)

(72) Inventor: Ichiro Iwasaki, Treviso (IT)

(73) Assignee: Arper S.p.A., Monastier di Treviso (IT)

(*) Notice: This patent is subject to a terminal disclaimer.

() Term: 15 Years

(21) Appl. No.: 35/505,396

(22) Filed: Jul. 6, 2018

(80) Hague Agreement Data

Int. Filing Date: Jul. 6, 2018

Int. Reg. No.: DM/102021

Int. Reg. Date: Jul. 6, 2018

Int. Reg. Pub. Date: Aug. 3, 2018

(30) Foreign Application Priority Data

Feb. 8, 2018 (WO) DM/101147

(51) LOC (12) Cl. 06-01

(52) U.S. Cl.

USPC D6/335
